UNITED STATES PATENT OFFICE

2,660,105

CHIMNEY CAP

Harold A. Sabin, Jr., Portland, Maine

Application May 11, 1949, Serial No. 92,611

4 Claims. (Cl. 98—78)

1

My present invention relates to the construction of chimneys and particularly to caps therefor.

Many chimneys prove unsatisfactory in use with their failure to function properly being most commonly attributable to inadequate draft due to improper design, the influence of down drafts, or soot deposits and creosote formations. It is the primary objective of this invention to provide a cap that may be attached to a chimney top to ensure adequate draft under all circumstances and to maintain the chimney in good condition. In accordance with my invention, I provide a chimney top consisting of a cap part extending upwardly from the upper end of the chimney and having ports adjacent its lower end of such peripheral extent that air may flow through the shell transversely or from end to end thereof. The upper end of the chimney is closed by a plate through which extends a conduit with its upper portion housed by but spaced from the shell and with its upper end below the upper end of the shell but above its ports. Preferably, both the shell and the hollow member are of frusto-conic form and a spark arrestor is attached to the lower end of the hollow member.

With such a cap, the conduit provides a flue outlet of substantially lesser cross sectional area than that of the chimney interior and preferably extends downwardly into the chimney to ensure that there is a head of warm gas adjacent the cap. The space between the conduit and the cap part provides a downward passage for down drafts while generally horizontal air currents pass transversely through the ports in the shell. These factors combine to ensure that a desired chimney draft exists that is essentially a thermal draft and that flue gases in the chimney are above the dew point thereby minimizing condensation, soot deposits, and creosote formations with the flue or flues.

In the accompanying drawings, I have shown illustrative embodiments of my invention from which these and other of its novel features and advantages will be readily apparent.

In the drawings:

Fig. 1 is a top plan view of the chimney.

Fig. 2 is a fragmentary view, in elevation, of a completed chimney in accordance with my invention.

Fig. 3 is a section, on an enlarged scale, along the lines 3—3 of Fig. 2.

Fig. 4 is a vertical section through a chimney showing a modification of my invention.

Fig. 5 is a vertical section showing another modification of my invention.

Fig. 6 is a view, in elevation, on a reduced scale of the chimney shown in Fig. 5.

In Figs. 1-3, I have indicated a chimney 10 having a flue 11 which is of the conventional rectangular cross sectional shape.

2

In the embodiment of my invention shown in the drawings, I close the upper end of the chimney 10 with a plate 12 having downturned edges 13 and a bottom flange 14 to enable it to be cemented as at 15 to the top of the chimney 10.

The plate 12 is centrally apertured to receive the conduit 16 and to support it preferably with its lower part extending downwardly into the flue 11. Attached to the lower end of the conduit 16 is a spark arresting screen element 17, preferably in the form of a basket. I have shown the conduit's upper end as protected by a hood 18.

At 19, I have indicated a cap part in the form of a shell attached to the plate 12 by spaced supports 20 of tubular stock so that air currents may enter or leave the shell 19 substantially without obstruction and regardless of their direction. While the supports may be otherwise anchored, I have shown them as locked to the plate 12. The shell 19 receives the upper part of the conduit 16 within it with the upper end of the conduit 16 positioned below the upper end of the shell 19 but above its ports defined by the supports 20 and with a substantial space between them. In practice, both the conduit 16 and the shell 19 are of frusto-conic section.

While the shell 19 may be otherwise formed, I have shown it as a metal casing 21 having cement 22 in its lower part and having its upper part filled with insulation as at 23.

In unusual circumstances as with tall chimneys or those in poor condition, an extension, conveniently consisting of tubular sections 24 may be connected to the lower end of the conduit 16 as suggested in Fig. 4. Such an extension is of sufficient length to extend below the zone of vapor condensation thereby ensuring that flue gases entrant of the member 16 are above the dew point.

In Fig. 5, I have shown an embodiment of my invention in which the cap part 19 is made from bricks so that a chimney, capped in accordance with my invention, will be more conventional in appearance. Where the cap is thus made, it is provided with a plurality of ports 25 adjacent the plate 26 and has its upper end closed by a plate 27 having a port 28 therein.

In practice, I have had good results with the upper end of the conduit 16 being approximately midway of the ends of the shell 19 and with its minimum diameter in the order of one-half the average of width of adjacent sides of the chimney interior. The height of the shell 19 is preferably one-half of the diagonal of the inside of the chimney and the lower portion of the conduit 16 is approximately one-half the length of its upper portion.

I have found that best results are obtained when the area of the upper end of the shell 19 is equal to the upper end of the conduit 16 but

that the space between the conduit 16 and the shell 19 may be varied appreciably.

With a chimney cap in accordance with my invention, the conduit 16 establishes a flue outlet of substantially less cross sectional area than that of the flue 11 into which it extends and, as a consequence, flue gases, discharged therethrough, have an increased velocity.

Should the chimney 19 be so located and dimensioned that down drafts are common that would normally enter the flue 11 to disrupt the up draft therethrough, such currents follow the path of least resistance and flow downwardly between the conduit 16 and the shell 19 and escape between the shell 19 and the plate 12. In this, 15 a contributing factor is that such down drafts tend to create an assisting suction at the base of the shell 19.

While the use of a hood 18 for the conduit 16 prevents moisture from entering the flue 11, 20 chimney caps in accordance with my invention minimize the effects of precipitation without such a hood as any precipitation entering the conduit 16 is directed thereby to pass downwardly into the flue without touching its walls. While such precipitation is not a serious factor when the chimney is heated, it contributes, in a cold chimney, to the deterioration of the cement.

In this connection, it will be noted that where the lower end of the conduit 16 extends below the plate 12, a head of warm gas is maintained at the upper end of the chimney in the zone 29. In addition, my caps prevent relatively cool outside air from entering the flue with the result that even during severe winter weather, the flue gases normally remain above the dew point so that condensation is held to a minimum. Condensation is objectionable in that it causes carbon to adhere to the walls of the chimney and creates liquid creosote.

From the foregoing, it will be apparent that chimney caps, in accordance with my invention, are of simple construction and, particularly when made in the proportions which I have specifically stated, ensure that satisfactory chimney performance may be obtained.

What I therefore claim and desire to secure by Letters Patent is:

1. A chimney cap for attachment to a chimney, said cap comprising a plate member to close the upper end of said chimney, an upwardly disposed conduit member supported by said plate member and opening through said plate member centrally thereof, said conduit member being, throughout its length, of substantially lesser cross sectional area than the upper end of said chimney, and a cap part approximately of frusto-conic form supported by said plate member and housing said conduit member in spaced relation thereto, said cap part extending above the upper end of said conduit member and having an upwardly opening vent of approximately the same area as the upper end of said conduit, and said cap part also having a plurality of openings adjacent said plate member and disposed about its periphery to ensure the free flow of air therethrough.

2. A chimney cap for attachment to a chimney, said cap comprising a plate member to close the upper end of said chimney, a conduit member centrally supported by said plate and opening therethrough with its upper end disposed a substantial distance above said plate member, said conduit member being, throughout its length, of substantially lesser cross sectional area

than the upper end of said chimney, and a cap part approximately of frusto-conic form supported by said plate member and housing said conduit member in spaced relation thereto, said cap part including inner and outer metal walls and thermal insulation therebetween extending above the upper end of said conduit member and having an upwardly opening vent of approximately the same area as the upper end of said conduit, and said cap part also having a plurality of openings adjacent said plate member and disposed about its periphery to ensure the free flow of air therethrough.

3. In a chimney cap for attachment to a chimney, a plate member to close the upper end of said chimney, an upwardly disposed conduit member supported by and opening through said plate member centrally thereof, said member being, throughout its length of substantially lesser cross sectional area than the upper end of said chimney, and a cap part supported by said plate member and housing said conduit member in spaced inwardly tapering relation thereto, said cap part extending above the upper end of said conduit member and having an upwardly opening vent of approximately the same area as the upper end of said conduit, said cap part including inner and outer metal walls both of frusto-conic form but meeting at said vent and thermal insulation between said cap walls and said cap part also having a plurality of openings adjacent said plate member and disposed about its periphery to ensure the free flow of air therethrough.

4. A chimney cap for attachment to a chimney, said cap comprising a plate member to close the upper end of said chimney, an upwardly disposed conduit member supported by said plate member and opening through said plate member centrally thereof, said conduit member being, throughout its length, of substantially lesser cross sectional area than the upper end of said chimney, and a cap part supported by one of said members and housing said conduit member in spaced relation thereto, said cap part extending above the upper end of said conduit member and being approximately of frusto-conic form and having an upwardly opening vent of approximately the same area as the upper end of said conduit, and said cap part also having a plurality of openings adjacent said plate member and disposed about its periphery to ensure the free flow of air therethrough.

HAROLD A. SABIN, JR.
